UNITED STATES PATENT OFFICE.

ETIENNE GIRARD, OF LOUISVILLE, KENTUCKY.

DESIGN FOR A CIGARETTE-HOLDER.

SPECIFICATION forming part of Design No. 27,375, dated July 20, 1897.

Application filed May 15, 1897. Serial No. 636,797. Term of patent 14 years.

To all whom it may concern:

Be it known that I, ETIENNE GIRARD, residing at Louisville, in the county of Jefferson and State of Kentucky, have invented and produced a new and original Design for a Cigarette or Cigar Holder, of which the following is a specification, reference being had to the accompanying drawing, forming part thereof.

10 The leading feature of my design consists in the ring-shaped portion, the shank extending from said ring-shaped portion, the twist at the end of the shank portion at the juncture of said ring and shank, and the free end of the shank bifurcated and curved.

15 Referring now more especially to the drawing, A represents the ring, which is fashioned after the pattern of a flat band.

B indicates the twist, and C the shank, said shank being bifurcated, the ends being curved, 20 as represented at D, and D' represents a rectangular-shaped band upon the shank. A cigar or cigarette holder fashioned in this manner is both useful and attractive.

Having thus described my invention, what 25 I claim as new, and desire to secure by Letters Patent, is—

The design for a cigar or cigarette holder, substantially as herein shown and described.

ETIENNE GIRARD.
